UNITED STATES PATENT OFFICE.

WILHELM G. ALDEEN, OF ROCKFORD, ILLINOIS, ASSIGNOR TO NATIONAL LOCK COMPANY, OF ROCKFORD, ILLINOIS, A CORPORATION OF ILLINOIS.

REFRIGERATOR HINGE.

Application filed August 7, 1922. Serial No. 579,976.

To all whom it may concern:

Be it known that I, WILHELM G. ALDEEN, a citizen of the United States, residing at Rockford, in the county of Winnebago and 5 State of Illinois, have invented a certain new and useful Refrigerator Hinge, of which the following is a specification.

The invention relates generally to hinges for doors and has particular reference to 10 refrigerator door hinges.

Refrigerator doors are usually ponderous and massive in construction; and are provided with tapered edges to fit into the door frame instead of over the latter, and with 15 a marginal rim for overlapping the frame to ensure a snug fit. Doors of this character require hinges of considerable strength to support them firmly in a closed position. In mounting such doors it is usually necessary to bend the hinge to conform precisely 20 with the thickness of the marginal rim so as to position the latter close to the door frame.

Heretofore it has been customary to provide hinges made of cast metal, but such 25 hinges are unsatisfactory because of their cost and because of the ease with which they are broken when being secured to the door. One of the primary objects of the invention 30 therefore is to provide an inexpensive hinge of considerable strength which can be bent to exactly fit the refrigerator door without being easily broken.

A further object is to provide a hinge of such design that it can be easily stamped 35 out of sheet metal, and will still have sufficient strength to carry a heavy load, and withstand a large clamping effect.

Refrigerator doors ordinarily place a 40 heavy stress upon the pivot pin of the hinge, which frequently results in loosening the base leaf from its mounting. This is obviously a very undesirable condition since the door when closed must be tightly clamped against the frame. A further object 45 therefore is to provide a hinge for refrigerator doors which will hold the door tightly in place and will not readily loosen from the door frame.

Another object is to provide a strong 50 hinge which is capable of receiving a better finish than that possessed by prior hinges.

Further objects and advantages will become apparent as the description proceeds.

In the drawings, Figure 1 is a front elevation of a hinge embodying the features of

my invention. Fig. 2 is a cross-sectional view of the hinge joint taken along the line 2—2 of Fig. 1. Fig. 3 is an edge view of the hinge secured to a refrigerator. Fig. 4 is a front elevation of a modified form of 60 the hinge. Fig. 5 is a cross-sectional view of the hinge joint taken along the line 5—5 of Fig. 4. Fig. 6 is a sectional view taken in the plane of dotted line 6 of Fig. 4. Figs. 7, 8 and 9 are sectional views on the order 65 of Fig. 5, showing alternative constructions.

Referring to Figs. 1, 2 and 3: The leaf 10 which is pressed from sheet metal, preferably brass or steel, may be of any desired shape. It is secured to the door *a* by screws 70 11 extending through the countersunk apertures 12. On both sides of the leaf 10 and near the hinge end thereof, inwardly extending projections 13 are provided. Said projections 13 abut the marginal portion of the door *a* and constitute locating stops; they also stiffen the leaf 10. A plurality of curls 14 are formed integral with the leaf 10. 75

As shown in Fig. 3, the base leaf 15 which is formed of sheet metal and is of any desired shape, is secured to the door frame *b* by screws extending through the apertures 16, 16^a. Four lugs 17 having apertures 18 therein are bent up from the base leaf 15. Two of these lugs lie at opposite ends of 80 the curl 14. The other two lugs lie within slots 19 formed between said curls. Before forming the lugs 17 from the base leaf 15, holes 20 are drilled at the base of said lugs so as to prevent the metal from breaking or 85 tearing in the corners when forming the lugs. By providing central lugs 17 as shown in Fig. 1, excessive strain on the screw passing through the central aperture 16^a may be resisted. 90

A hinge pin 21 extends through the curl 95 14 and the lugs 17.

In Fig. 4 two end curls are formed from leaf 10 in spaced relation. A curl 22 is formed on the base leaf 15^a so as to fit 100 within the space between the end curls 14^a. Two lugs 17^a on the base leaf 15^a lie at opposite ends of the series of curls 14^a and 22.

In Fig. 7 the hinge differs from that 105 illustrated in Fig. 1 in that the lugs 17^b are three in number instead of four, there being one at each end and one at the center instead of two near the center. Two curls 110 are formed from the leaf 10 and are spaced

apart to provide a slot between them to receive the intermediate lug.

In Fig. 8 the hinge differs from that shown in Fig. 1 in that the center lugs 17^a of the base leaf are formed near the ends instead of near the center.

In Fig. 9 the hinge differs from that represented in Fig. 1 in that the base leaf has only two lugs 17^a instead of four and the said lugs are formed near the ends instead of at the ends or near the center.

In manufacturing refrigerators, the thickness of the marginal portion of the door varies in different makes of refrigerators. 15 When ordering hinges the refrigerator manufacturer specifies the amount of "offset" to be provided between the leaves of the hinge to accommodate the marginal or overlapping portion of the door. The casting process does not permit the precision necessary to produce hinges having the exact "offset" desired, whereas the formed-metal hinge of the present invention can be made with absolute accuracy.

20 25 I claim as my invention:

1. A refrigerator door hinge comprising two sheet metal stampings forming respectively a base leaf and a door leaf, the base leaf being in the form of a flat plate having three or more alined pintle supporting lugs struck up from the plate in spaced relation substantially midway between opposite side edges of the plate and having registering apertures therein; and the door leaf 30 35 having a plurality of curls at one end providing pintle bearings adapted to interengage and aline with the apertures in said

lugs, and a pintle entered through said aperture and bearings to connect the leaves hingedly together.

2. A refrigerator door hinge comprising two sheet metal stampings forming respectively a base leaf and a door leaf, the base leaf being in the form of a flat plate having four alined pintle supporting lugs struck up from the plate in spaced relation substantially midway between opposite side edges of the plate, the adjacent lugs forming pairs, and the door leaf having three 40 45 50 curls at one end providing pintle bearings adapted to enter between said pairs of lugs and aline with the apertures therein, and a pintle entered through said apertures and bearings to connect the leaves hingedly together.

3. The combination with a refrigerator having a door with its outer face offset outwardly from the face of the door frame, of a hinge comprising two sheet metal stampings forming respectively a base leaf secured flat upon the door frame and a door leaf secured upon said offset face of the door, said leaves having interengaging portions pivotally connected together, and the door leaf having flanges at its upper and lower edges for stiffening the leaf, said flanges being further adapted to abut the offset edge of the door so as to serve as positioning stops determining the location of the door leaf with respect to the edge 55 60 65 70 of the door.

In testimony whereof, I have hereunto affixed my signature.

WILHELM G. ALDEEN.
